BOMB RELEASE MECHANISM

Harry F. Vickers, Washington, D. C.

Application November 4, 1935, Serial No. 48,085

3 Claims. (Cl. 89—1.5)

This invention relates to bomb release mechanism and has to do particularly with the combination of positive locking but instant releasing mechanism.

5 Heretofore, in supporting bombs in airplanes and the like, it has been the practice to releaseably latch the bomb or bombs in position by various suitable forms of latches backed by spring means, the tension of such spring means being 10 such as to permit the release of the bomb by manual power or by a remote control solenoid, or other form of releasing means which has acted directly against the spring means. Many bombs have been accidentally released because 15 springs light enough to permit action by manual power, solenoids or the like have been overcome by jarring or vibration.

It is the object of the present invention to provide a simple, compact and light-weight mechanism for positively latching the bombs in place, but at the same time, permitting instantaneous release when desired. More specifically, the object of the present invention is to utilize positive means such as a strong spring for holding 25 the bombs in position and to store energy in a small body such as a rapidly moving fly-wheel, for use in instant release of the latching means, in combination with remote control means for actuating the release mechanism.

30 Other features have to do with a single revolution clutch mechanism, in combination with the releasing mechanism as a whole, together with features of structure and arrangement as will be more clearly brought out in the specification and 35 claims.

In the drawing:

Fig. 1 is a diagrammatic view of a bomb release mechanism embodying the features of my positive latching but instantaneous releasing 40 mechanism.

Fig. 2 is a perspective detail view of one form of standard one shot clutch mechanism utilized as a part of my release mechanism.

The various mechanisms for carrying out the 45 present invention are more or less standard and it will be understood that the present invention resides more in the combination of elements for providing safety latching and instantaneous release rather than in the mechanism for carrying out such objects.

In Fig. 1, I have shown a bomb 2 having straps 3 supported by latches 5 of a release member generally designated 4. It will be seen that as long as the release member 4 holds the latches 5 against the stops 6 that the bomb will be held

in normal position. A strong spring 7 is shown as means for holding the releasing means against the stops. It will be understood, however, that any type of latching means may be used, the idea here being that some form of latching 5 means is provided and is resiliently and firmly held in normal latching position.

Closing and opening of the release means 4 is controlled by means of a pivoted lever 8 actuated by an eccentric 9. A source of power for 10 actuating the eccentric 9 is preferably in the form of a high speed motor 10 connected to a fly-wheel 11. Both the motor and fly-wheel may be very small; for example, the fly-wheel 15 may be around five pounds and normally rotated at about 10,000 R. P. M.

Reduction gearing 12 may be interposed between the fly-wheel and the eccentric member 9. One of the reduction gears 13 is preferably connected to a pinion 13a through a "one shot" 20 clutch member 14. This clutch may be of the same type as the usual punch press clutch, but is preferably very small and compact and similar in size and weight to one shot clutches such as used to shift the carriage on electrical type-writers. A typical one shot clutch mechanism that may be utilized in connecting the gear 13 with the pinion 13a is illustrated in perspective in Fig. 2. In this structure, the gear 13 and shaft 14 rotate continuously, as long as the motor 30 10 is in operation; a ratchet clutch 15 rotates continuously with the shaft 14. A cam and ratchet clutch member 16 is slidably keyed to a shaft 17, which shaft in turn carries the pinion 13a. A collar 18 permanently attached to the 35 shaft 17 positions a spring 19 to normally urge the clutch member 16 to the right, as viewed in Fig. 2.

The ratchet clutch 16 is normally restrained from engaging the ratchet clutch 15 by a lever 40 20, which lever is free to rotate about a shaft 21 but does not slide longitudinally of the shaft. The control mechanism for this lever, and hence the clutch 16 may be best understood by describing the operation thereof: Upon pressing the 45 control lever 22 downwardly, the cam rod 23 is pulled rearwardly and catches the lower end of the lever 20, rotating the same and in clockwise direction about the shaft 21. This rotation of the lever 20 about the shaft 21 frees the cam 50 member 16 and the ratchet clutch parts are allowed to engage, thus causing rotation of the shaft 17 and the pinion 13a.

Due to the arc of movement, the lower end of the lever 20 will slip off of the cam rod 23, as the 55

movement of the lever 22 is completed; thus with one continued downward movement of the lever 22, the lever 28 will move in a clockwise direction, and then when it slips off of the cam rod 16, it will immediately return to its normal position, and as the cam member 16 rotates and completes its single rotation it will gradually be disengaged from the ratchet clutch 15. The cam rod 23 protrudes through suitable slide brackets 24 and 25, and these brackets are slotted as shown to permit general vertical movement of the cam rod. The end of the cam rod 23 is tapered as at 26, and the cam rod is held normally in an upward position by a spring 27; when the lever 22 is released, the spring 27 will permit the cam rod 23 to move downwardly and the tapered surface 26 to move past the lower end of the lever 28 so as to assume the normal position of the parts as shown in Fig. 2. Instead of using a mechanical actuating member 22, this "one shot" or single revolution clutch may be actuated by a solenoid generally designated 30 and controlled from a remote point 31, as shown in Fig. 1.

25 The relation between the gear 13 and the eccentric 8 is one to two so that each time the clutch gear 13 makes one revolution, the eccentric gear 8 makes a half revolution. The pinion 13a of the gear 13 and the gear 8 are so meshed that when the "one shot" clutch mechanism stops, the eccentric of the gear 8 will be in either of two extreme positions, that is, the pivoted lever 8 will be moved either to the right to latching position or to the left to releasing position. Thus actuation 30 of the solenoid to actuate the "one shot" clutch will move the lever 8 say to release position and stop, a second actuation of the solenoid and a second actuation of the clutch member will move the lever 8 back to the normal latching position.

35 It will thus be seen that all the parts in my releasing mechanism are small and compact, energy is stored in the high speed fly-wheel sufficient to effect instant release of the member 4 and the bomb, upon actuation of the solenoid 30, or any other means such as the mechanical trip 22 which 40 will actuate the "one shot" clutch. This release will take place even if all the parts of the release mechanism and the bomb are coated with ice as the rapidly rotating fly-wheel and the reduction gear train represents a large amount of power.

The spring 7 is a very strong one to be absolutely sure that regardless of the vibration or other shocks to which the mechanism is subjected, the bombs will not be released. In other words, I have provided an extremely strong preloaded latch in combination with a rather light but positive acting releasing means for said preloaded latch. This represents an important safety feature in that the bomb is positively retained in normal position and there is no possible release of the same until actuation of the "one shot" clutch. 5

10 It will be understood that the motor 10 and fly-wheel 11 may be placed in operation some time prior to actuation of the "one shot" clutch.

What I claim is:

15 1. Bomb retaining and release mechanism comprising, means to hold a bomb in position, light weight high speed motive means, and motion transmitting means between said first means and said motive means whereby said first means may 20 be actuated to release a bomb, including a clutch normally disconnecting said first means and said motive means and means for actuating said clutch to connect and disconnect said first means and said motive means.

25 2. Bomb retaining and release mechanism comprising, means including a relatively strong pre-loading means to hold a bomb in position, light weight high speed motive means, and motion transmitting means between said first means and said motive means whereby said first means may 30 be actuated to release a bomb, including a control unit normally disconnecting said first means and said motive means and means for actuating said control unit to connect and disconnect said first means and said motive means.

35 3. Bomb retaining and release mechanism comprising, means to hold a bomb in position, relatively strong preloading means for positively maintaining said first named means in position, 40 light weight high speed motive means, and motion transmitting means between said first means and said motive means whereby said first means may be actuated to release a bomb, including a one shot clutch normally disconnecting said first means and said motive means and means for actuating said clutch to connect and disconnect said first means and said motive means.
